UNITED STATES PATENT OFFICE.

ARTHUR O. AUSTIN, OF BARBERTON, OHIO, ASSIGNEE, BY MESNE ASSIGNMENTS, TO THE OHIO BRASS COMPANY, OF MANSFIELD, OHIO, A CORPORATION OF NEW JERSEY.

PROCESS OF PRODUCING A REPAIR IN FABRICS.

1,424,332.

Specification of Letters Patent.

Patented Aug. 1, 1922.

Application filed May 12, 1920. Serial No. 380,827.

To all whom it may concern:

Be it known that I, ARTHUR O. AUSTIN, a citizen of the United States, residing at Barberton, in the county of Summit and 5 State of Ohio, have invented certain new and useful Improvements in Processes of Producing a Repair in Fabrics, of which the following is a specification.

This invention has for its object the provision of means for repairing fabrics and especially fabrics of what are known as filter press sacks, so that said sacks when repaired shall retain their usefulness.

Another object of the invention is to provide an improved process for producing such repairs.

The invention is exemplified in the combination and arrangement of parts shown in the accompanying drawing and described 20 in the following specification, and also in the steps of the process described in the specification.

The invention is more particularly pointed out in the appended claims.

25 In the drawing—

Fig. 1 is a fragmentary vertical section illustrating diagrammatically a filter press with filter press sacks in place.

Fig. 2 is a transverse section of the structure shown in Fig. 1.

Fig. 3 is a fragmentary view showing one corner of the press sack which has been worn by use.

Fig. 4 shows the same press sack after it 35 has been repaired. Figs. 3 and 4 are both somewhat diagrammatic.

Fig. 5 is a diagrammatic vertical section of a vulcanizer illustrating one step in the process of repairing press sacks.

40 In the preparation of various substances for commercial use, such as the clay from which porcelain articles are manufactured, the material is mixed with water in order to secure a uniform mixture and is then 45 placed in a filter press by means of which the water is expelled under pressure from the mixture leaving the clay in a plastic state. A portion of such a press is shown diagrammatically in Fig. 1 in which the numeral 10 designates the plates of the press 50 which have aligned central openings 11 and enlarged bands or ribs 12 which extend around the openings 11 and are located adjacent the edges of the plates. The plates 55 10 are supported on bars 13 extending longi-

tudinally of the press and mechanism, not shown, is provided for clamping the plates against one another. A filter sack, shown at 14, comprises a pair of fabric sheets, one of which lies on each side of a plate 10, the two sheets being secured together at the opening 11 and having the outer edges clamped between the enlarged portions 12 of the plates 10. The sheets 14 may be removed from the plates 10 after the plates are separated from one another by drawing one of the sheets 14 through the opening 11. In assembling the press ready for operation, the filter sack is placed upon the plate by first feeding one of the two attached sheets of the sack through an opening in the plate 10 and then spreading the two sheets over opposite sides of the plate. The plates are then clamped together so that the edges of sacks on adjacent sides of contiguous plates are clamped between the adjacent rims of the plates. The material to be filtered is then fed, under pressure, through the openings 11 into the various chambers of the press and will force the fabric of the sacks against the walls of the plates 10 and cause the water to be filtered through the fabric and to escape through ducts 15 provided for that purpose. The surfaces of the plates may also be provided with radially extending grooves to facilitate the escape of the water from the mixture. The plates must be clamped sufficiently tight against the edges of the sacks to prevent any leakage between the cooperating rims of the plates.

It is apparent that after a sack has been used for some time, it is likely to be worn at the points of contact with the rims of the filter press plates while the remaining portion of the sack is practically unworn. It 95 will be readily seen that when this occurs the mixture within the press will escape at the places where the sack is worn and thus impair the efficiency of the press and give rise to loss of material. Heretofore it has 100 been impossible to repair a sack thus worn for the reason that any patch placed upon the sack produces an unevenness in the thickness of the fabric so that it is impossible to procure a tight joint by clamping 105 the fabric between the rims of the press plates. Under the present invention a sack having a frayed place or small opening, such as is illustrated at 16 in Fig. 3 of the drawing, is repaired by filling the opening or 110

frayed place with rubber or other material which can readily be cured or hardened by heat or chemical means. The repairing is preferably done on a steam-heated vulcanizing table or between surfaces which will squeeze down the repairing material to the same thickness as the press sack. The method of operation is illustrated in Fig. 5 in which 17 and 18 are the two plates of a vulcanizer having the sack 14 to be repaired in position between the plates. If a comparatively large opening, like that shown at 19 in Fig. 3, is to be repaired, a piece of fabric 20 of the same thickness as the sack, 15 and cut to conform roughly to the shape of the opening, is placed in the opening, and the space between the edges of the patch and the edges of the opening is filled with the vulcanizing material as shown at 21 in Fig. 20 5 of the drawing. If the hole is smaller, it may be completely filled with the vulcanizing material as shown at 22 in Fig. 4. After the parts have been clamped between the plates 17 and 18 of the vulcanizing press 25 and the vulcanizing material has been sufficiently cured, the patch 20 will be firmly held in place and form a continuation of the fabric of the sack. The repaired portion will be of the same thickness as that of the 30 original fabric and there will be no thickened portions to permit leakage of the substance to be filtered when the sack is in place in the filter press. By using rubber or other material which will adhere to the 35 fibers of the press sack or filter cloth, it is possible to repair either large or small holes with ease, and in practically any place on the filter cloth, as the thickness of the cloth is not altered. Where rubber is used the curing 40 may be performed by applying heat to cure the rubber cement or rubber stock when heated, or the rubber may be cured by the so-called "acid cure" or any other. By this process a repair may be effected without increasing the thickness of the filter sack and 45 furthermore, the method may be used to join sacks of a filter fabric of the same or different textures. The vulcanizing method may also be used to prevent raveling and to 50 eliminate sewing in complicated press sacks.

I claim:

1. The method of repairing fabric of filter press sacks or other articles which comprises the insertion of vulcanizable material in the 55 portion of the fabric to be repaired, and curing said material to cause it to adhere to said fabric and form a continuation of the body thereof.
2. The method of repairing fabric of press 60 sacks and other articles comprising the insertion of vulcanizing material in the fabric to be repaired, holding said material and

fabric between two surfaces to impart to said material a thickness equal to the thickness of said fabric, and curing the material 65 to cause it to adhere to said fabric and fill the opening to be repaired therein.

3. The process of repairing filter sacks and other articles which comprises the insertion of a piece of fabric within an opening 70 to be repaired so that said piece of fabric has the faces thereof substantially flush with the surface of the fabric of said sack and so that the edges of the inserted piece lie opposite and do not overlap the edges of the fabric of said sack, and securing said piece of fabric in place in the opening in said sack by vulcanizable material. 75

4. The process of repairing filter sacks and other articles comprising the insertion 80 of a section of fabric into an opening in the article to be repaired, said section being shaped to conform approximately to the shape of said opening and lying wholly within said opening, and securing said section in position in said opening by means of vulcanizable material distributed about the edge of said section and adhering to the edge thereof and the adjacent edge of the 85 opening in the article to be repaired. 90

5. The process of repairing filter sacks and other articles comprising the insertion of a section of material within an opening to be repaired so that said section of material lies entirely within said opening without overlapping, and securing said section of material in place in said opening by a vulcanizable substance and curing said substance between adjacent faces of a press to impart to said vulcanizable substance the 100 same thickness as the repaired article. 95

6. The process of repairing an opening in the fabric of a filter press sack comprising the insertion of vulcanizable material in said opening, and curing said material between 105 adjacent faces of a vulcanizing press to impart to the filling material in said opening the same thickness as that of the fabric repaired thereby.

7. The process of repairing the fabric of 110 filter press sacks and other articles comprising the insertion of vulcanizable material within an opening in said fabric to be repaired, curing said vulcanizable material to cause it to adhere to the fibers of said fabric 115 and be retained in place in said fabric, and maintaining said material substantially equal in thickness to the thickness of said fabric during said curing operation.

In testimony whereof I have signed my name to this specification on this 7th day of May, A. D. 1920.

ARTHUR O. AUSTIN.
